UNITED STATES PATENT OFFICE.

THOMAS C. SMITH, OF SEATTLE, WASHINGTON.

ENGINE PISTON AND METHOD OF PACKING AND LUBRICATING THE SAME.

Application filed August 10, 1922. Serial No. 580,848.

To all whom it may concern:

Be it known that I, THOMAS C. SMITH, a citizen of the United States of America, and resident of the city of Seattle, in the county of King and State of Washington, have invented certain new and useful Improvements in Engine Pistons and Methods of Packing and Lubricating the Same, of which the following is a specification.

10 My invention relates to engine pistons and particularly to the method and means employed whereby the packing and lubricating of the surfaces of the piston which contact with the cylinder is secured.

15 The object of my invention is to provide means and a method whereby engine pistons may be packed so as to work at all times tightly and without leakage, and at the same time, to furnish an efficient lubrication between the piston and cylinder surfaces.

20 My invention consists of the novel means and method employed whereby a compound of such character that it will flow slightly under pressure, is carried in the piston and is fed as necessary to the periphery of the piston so as to at all times maintain a sealed contact between the piston and the cylinder, and to provide therefore, a highly efficient lubrication.

25 The manner of carrying out my method and a preferred type of means for doing the same is illustrated in the accompanying drawings.

Figure 1 is a longitudinal section taken 30 through a piston constructed in accordance with my invention.

Figure 2 is a transverse section of the same piston taken upon the planes indicated by the broken line 2-2 of Figure 1.

35 One of the difficulties found in the operation of engines, and particularly of engines of the internal combustion type, is to maintain a tight non-leaking joint between the piston and the cylinder, and to furnish a thoroughly efficient lubrication between the same surfaces. The improved method which is a part of my present invention consists in providing a storage chamber or cylinder within the piston for the reception 40 of a compound which is of such character that it may be made to flow under pressure and one which is also an efficient lubricant, and to provide the piston also with a peripheral groove having communication with a 45 storage chamber in the piston, so that this

groove is at all times maintained full of the compound which is thereby held out into close contact with the cylinder walls, thus maintaining a tight joint, and the compound being also a lubricant, the cylinder walls are 50 effectively lubricated.

The exact character of the compound employed may be varied. There are a number of lubricants and lubricating compounds which may be adapted for this purpose. 55 The compound which I consider as being most effective for this purpose is one consisting of powdered graphite or of graphite mixed with other materials, the same being of such consistency that it will flow from 60 the interior chamber to the peripheral groove. It is evident that other materials and compounds might be employed.

The construction of the piston which I prefer to employ for carrying out my invention is illustrated in the drawings. In these the piston is composed of two main sections, an inner or lower section 1 and an upper or outer section 2. These two sections are so constructed and secured together as 65 to form a chamber or cylinder 3 within the piston, which chamber is filled with the packing and lubricating compound. The manner of securing these two sections together as illustrated, is to provide them with 70 complementary threaded surfaces as shown at 75 12. The lower section of the piston is provided with a shoulder at 10 against which the lower edge of the upper or cap section 2 abuts. The upper or cap section 2 is also 80 provided with a peripheral groove 20 and at each side of this with a groove or grooves as 85 21 for the reception of packing rings of any suitable or ordinary character. The groove 20 communicates with the interior storage 90 chamber or cylinder 3 through the means of a series of ports 22 distributed about the periphery of the piston.

95 Within the cylinder 3 formed in the cap of the piston is placed a follower or floating 100 piston 4. This may also be provided with a packing ring as 40. It is normally held pressed towards the piston head by means of springs 5 which are placed within bores 105 11 formed in the lower or inner section 105 of the piston. These, acting upon the compound contained in the chamber 3, tend to cause it to flow through the ports 22 into the outer or peripheral groove 20. At the same 110 time the mass of the piston 4 under the re-

ciprocating action of the piston tends to act as a hammer to give the compound a blow at each reciprocation, thus tending to drive it outward so as to keep the peripheral groove at all times filled with the compound.

The head of the piston is provided with a threaded bore containing a plug 6 which may be removed when desired and through which a supply of the compound may be forced into the chamber 3 and the springs 5 compressed whenever this may be necessary. A charge of the compound in the chamber 3 will last for a long time and it will only be rarely necessary to re-charge the same.

15 The lower portion of the cap 2 which screws upon the lower section of the piston, preferably extends down to a point somewhat below the lower level of the wrist pin. The bore 7 for the reception of the wrist pin 20 is made through both of the piston sections after the two have been screwed to their final operating position. The wrist pin, therefore, or rather, the bushing therefor which is pressed into the bore 7, acts as a lock to prevent the possibility of the two sections of the piston becoming separated.

By the method herein described a tight seal may be secured between the piston and the cylinder walls. The material employed for this being a highly efficient lubricant, will maintain reciprocation such that there will be no observable wear of the cylinder wall. The piston also will maintain a tight fit so that there will be no leakage of gas past the piston. Therefore, the frictional resistance caused by the movement of the piston in its cylinder will be reduced and wear of the piston and cylinder will also be minimized. In consequence a long life of both 35 piston and cylinder may be secured while

at the same time maintaining a thoroughly efficient joint between the two.

What I claim as my invention is:

1. An engine piston having a groove in its periphery and a compression grease chamber 45 communicating with said groove, a piston in said chamber and springs acting upon said piston to force the grease towards said groove.

2. An engine piston having a removable 50 cap forming the outer head of the piston, and a chamber closed by said cap, the piston also having a peripheral packing groove communicating with said chamber and piston rings at each side of said packing groove. 55

3. An engine piston comprising a lower and an upper section screwing together and forming between them a compound containing cylinder, a piston fitting said cylinder, the upper of said piston sections having an 60 exterior peripheral groove and channels communicating with the compound containing cylinder, the piston having a wrist pin bore extending through both sections.

4. An engine piston comprising a lower 65 and an upper section screwing together and forming between them a compound containing cylinder, a piston fitting said cylinder, the upper of said piston sections having an exterior peripheral groove and channels communicating with the compound containing cylinder, the lower of said piston sections having spring receiving bores and springs 70 therein acting upon the piston in the compound containing chamber to force the compound out into the peripheral groove. 75

Signed at Seattle, King County, Washington, this 4th day of August 1922.

THOMAS C. SMITH.
